BY DR. E. Evans:
ATTORNEY.

UNITED STATES PATENT OFFICE.

HENRY EDMOND MARCEL, OF LONDON, ENGLAND.

APPLIANCE FOR WAVING OR TREATING HAIR.

1,263,582.

Specification of Letters Patent. Patented Apr. 23, 1918.

Application filed April 4, 1916. Serial No. 88,893.

To all whom it may concern:

Be it known that I, HENRY EDMOND MARCEL, a subject of the King of Great Britain and Ireland, residing at 534 Oxford street, 5 London, W., England, have invented certain new and useful Improvements Relating to Appliances for Waving or Treating Hair, of which the following is a specification.

This invention relates to appliances for 10 waving or treating the hair of the type in which the hair is wound upon a support and inserted into a casing and retained there while subject to moist heat whereby the hair is more or less permanently waved or treated. 15 Appliances for this purpose are known in which the hair is heated by means of an electric resistance coil, and the object of the present invention is to provide an appliance of the kind in which the heating is not dependent upon a resistance coil but is effected 20 without liability to burning the hair by the use of a mass of metal which is first heated and then introduced into the apparatus.

According to the invention a heater is provided 25 formed essentially of a central tube within which the hair curled or wrapped in a moist paper or other covering is introduced and a surrounding and removable massive sleeve of metal or other material 30 capable of being heated to a high degree, a surrounding casing being advantageously employed capable of being applied over the central tube and the massive sleeve after the latter has been placed in position upon the 35 central tube. On the massive sleeve being heated and placed in position on the central tube the latter will be heated and the heat retained for such time as effectively to treat the hair inserted within the tube.

40 The invention comprises the construction of apparatus hereinafter described.

The invention is illustrated by way of example in the accompanying drawing which represents in Figure 1 an elevation partly 45 in section of one construction, and in Fig. 2 a cross-section on the line $x-y$ Fig 1.

In carrying the invention into effect as 50 illustrated in the accompanying drawing a central tube a is provided for the reception around it of a massive sleeve b which may be made of a suitable alloy of metal in which aluminium is incorporated so that while the sleeve b is massive it is nevertheless not very heavy. A casing c serves to inclose the massive sleeve b .

In the illustrated construction the casing

c and the central tube a are connected together by which an annular space is formed between them closed at the top and open at the bottom. The central tube a extends beyond the lower edge of the casing c and the casing is provided with a handle h by means of which the combined casing and tube may be held so that the lower extremity of the tube a may be inserted within the sleeve b and thus the sleeve b may be introduced within the casing without the necessity of the sleeve in its heated condition being otherwise handled.

In the illustrated construction the sleeve b is provided with a number of internal longitudinal ribs b^1 at intervals which may be formed by providing in the upper part of the sleeve corresponding internal longitudinal recesses, so that thus the sleeve b contacts with the central tube a through the ribs b^1 only, so that the area of the heated sleeve in contact with the central tube is minimized and a rapid distribution of heat from the massive sleeve and the excessive heating of the central tube are prevented. Furthermore pins d are provided at the upper and lower ends of the sleeve b through which contact is made with the upper end of the casing and the lower cover e . The latter is provided with a rim by which it may be fitted within the lower open end of the casing c .

The cover e is provided with a central hole to accommodate the lower protruding extremity of the central tube a . The cover e is mounted upon a heat non-conducting ring f of vulcanite or other suitable material, the cover e being mounted thereon by means of pins g as illustrated. By such means space is available for the application thereon of that part of the hair that is not being treated. The heater thus provided is applied in position close to the head with the ring f in contact with it. By such means the hair curled or wrapped in a moist paper or other covering may be inserted into the tube and the hair treated very nearly to the roots.

The central tube may be provided of copper, aluminium or any other suitable metal.

In the case of apparatus intended for treating hair near the roots only, the sleeve may be relatively short and contact may be made with the central tube near the lower end only.

It is preferred to provide the central tube

and the base completely open at each end but the central tube may be provided open at one end only and holes at the other end in suitable position for the escape of steam.

5 In use the appliance may be suspended from a balanced fitting in order to relieve the weight of the appliance from the head, but it is one of the objects of the invention to produce the appliance as light as possible 10 and to reduce the total weight to a minimum.

I claim:

1. An appliance for waving or treating the hair comprising essentially a central heating tube through which the hair to be 15 waved or treated is introduced and a removable massive sleeve capable of being heated and applied upon the tube for heating the hair within it.

2. An appliance for waving or treating the hair, comprising essentially a central heating tube through which the hair to be waved or treated is introduced, a removable massive sleeve capable of being heated and applied upon the tube for heating the hair 20 within it, and a casing for surrounding the removable massive sleeve.

3. An appliance for waving or treating the hair, comprising essentially a central heating tube through which the hair to be 25 waved or treated is introduced, a casing

forming with said central heating tube an annular space and a removable massive sleeve capable of being heated and applied upon the said tube within the said annular space for heating the hair within the tube. 35

4. An appliance for waving or treating the hair, comprising essentially a central heating tube through which the hair to be waved or treated is introduced, a non-conducting base upon which said central heating tube is mounted and a removable massive sleeve capable of being heated and applied upon the tube for heating the hair 40 within it.

5. An appliance for waving or treating the hair, comprising essentially a central heating tube through which the hair to be waved or treated is introduced, a casing forming with said central heating tube an annular space, a non-conducting base upon 45 which the said tube and casing may be applied and a removable massive sleeve capable of being heated and applied upon the said tube and within the said annular space for heating the hair within the tube. 50

HENRY EDMOND MARCEL.
